WATCH BOX

Francis E. Blod, Tuckahoe, N. Y., and Alfred M. Blumenfeld, Hackensack, N. J., assignors to The Gruen Watch Company, Cincinnati, Ohio, a corporation of Ohio

Application September 21, 1950, Serial No. 12,281

Term of patent 14 years

(Cl. D80—5)

To all whom it may concern:

Be it known that we, Francis E. Blod and Alfred M. Blumenfeld, both citizens of the United States and residing at Westchester County at Tuckahoe, New York and Bergen County at Hackensack, New Jersey, respectively, have invented a new, original, and ornamental Design for a Watch Box, of which the following is a specification, reference being had to the accompanying drawing, forming a part thereof.

Figure 1 is a top plan view of a watch box showing our new design.

Figure 2 is a front elevational view thereof.

Figure 3 is an end elevational view thereof.

We claim:

The ornamental design for a watch box, substantially as shown.

FRANCIS E. BLOD.

ALFRED M. BLUMENFELD.
